(57) **CLAIM**

The ornamental design for a cannula pad, as shown and described.

DESCRIPTION

FIG. 1 is a front, top and right side perspective view of a cannula pad embodying our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines illustrate perforation lines that form a part of the claimed design.
